UNITED STATES PATENT OFFICE

2,240,563

ZERO ELIMINATING MEANS

Clair D. Lake, Binghamton, and Francis E. Hamilton, Endicott, N. Y., assignors to International Business Machines Corp., New York, N. Y., a corporation of New York

Original application August 31, 1938, Serial No. 227,784. Divided and this application June 14, 1939, Serial No. 279,013

10 Claims. (Cl. 197—20)

This case relates to a machine for automatically transcribing information derived from a record source, and is a division of our application Serial No. 227,784, filed August 31, 1938.

The machine deals specifically with an information source comprising record or tabulating cards bearing information in the form of coded perforations or designations. The record card has parallel columns of index positions variously perforated according to a selected code to represent the desired information. A group of adjacent columns may be assigned to numerical data and this group may be referred to as a numerical card field. Each column of such field corresponds to a different denominational order, and there are as many such columns as the number of denominational orders of the highest numerical value which may be perforated into the numerical field. When the field is to be perforated with a numerical item having fewer denominational orders than the number of columns, it is the practice to punch zero designations into those columns preceding the column bearing the first significant figure.

The object of the present invention is to provide novel means to eliminate the recording or transcribing of zero designations of a numerical card field preceding the first significant figure designation of the field.

More specifically, this object includes the provision of means to prevent the analysis of zero designations preceding the first significant figure of a numerical representation in the numerical card field.

The transcribing apparatus with which the present invention is associated comprises means controlled in succession by the numerical designations of the record card for recording on a record receiving sheet the digits of the number in succession. The invention contemplates the provision of means for preventing the zero digit designations preceding the first significant digit designation of a numerical card field from being recorded and instead causing an intra-line spacing of the record receiving sheet for each of the card columns bearing a zero designation preceding the first significant figure.

The machine operates cyclically on the record cards, performing one cycle for each card. A stack or series of related record cards may have correspondingly located numerical fields. It is an object of the invention to provide zero eliminating means which is automatically placed in effect at the same time during each of successive cycles of operation on successive record cards to

prevent the recording of zeros preceding the first significant figure designated in the numerical field of successive cards.

The latter object may be stated as the provision of program means for eliminating the recording or transcribing of zeros preceding the first significant digit of the number designated in columns of a numerical field of a series of records. Further, it is contemplated to provide such program means as is settable in accordance with differently located numerical card fields.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the machine with the control section uncovered;

Fig. 2 is a section along lines 2—2 of Fig. 1;

Fig. 3 is a detail sectional view through a part of the card stacking unit of the control section, taken along lines 3—3 of Fig. 1;

THE TRANSCRIBING UNIT

While the invention may make use of any suitable recording unit, it is preferred, for illustrative purposes, to disclose the invention herein in connection with a recording apparatus, the general principles of which are disclosed in Patents Nos. 1,777,055 and 1,873,512. Fig. 1 shows the arrangement of levers 10 for causing the operation of transcribing elements and related control devices. The several levers 10 may be distinguished by appending to the general reference character a supplementary reference character denoting the particular function or operation controlled by the operating lever. Thus, levers 10—A to Z, 0 to 9, cause operation of transcribing elements to record characters A to Z, 0 to 9; lever 10—TAB controls tabulating operation; lever 10—SH controls the case shift mechanism; lever 10—CR controls the carriage return operation; and lever 10—SP controls the operation of intra-line spacing means.

Referring to Fig. 6, depression of a lever 10 releases a latch 11 from a cam 12 permitting the cam to be forced by a lever 13 against a constantly rotating friction shaft 14. The shaft rotates the cam, causing the carrier 15 of the cam to rock in a direction for depressing connected link 16. This link, through a linkage 17, propels a type bar 18, mounted on type basket 19, against the sheet of paper P on the platen 20, thereby typing the character corresponding to the depressed lever 10. During the end of the stroke of type bar 18, it strikes a universal bar 22 to actuate the escapement control 23 for effecting a character or intra-line spacing operation of the carriage 24. Operation of the space lever 10—SP acts through associated elements 11, 12, 13, 15, and 16 to operate a linkage 25 for actuating escapement control 23 also to cause an intra-line spacing operation of carriage 24.

A special, normally closed switch 28 (Fig. 14) is located at the rear of the recording unit. The long, spring blade of this switch is engaged with a roller 30, of insulating material, carried by one arm of a lever 31. This lever is the back-space interlock, which as described in Patent 1,873,553 is rocked by the escapement pawl release lever 32 while the carriage is tabulating. Lever 32 is also actuated during line space or carriage return operation to rock back-space interlock lever 31, as described in above-mentioned Patent 1,955,614. When lever 31 is rocked, its roller 30 opens switch 28, which remains open until the completion of either the carriage return or the tabulating operation, whichever is taking place. The purpose of switch 28 will be explained hereinafter, in connection with the circuits.

Another special, normally closed switch 33 is provided (Fig. 15) at the rear of the recording unit, which is opened when an insulating tab 33a

on its long, spring blade 33b is engaged by the special extension 34a of the scitable "beginning of the line" margin stop 34. The purpose of switch 33 will be explained in connection with the circuits.

RECORD CARD AND CODE

The record card T, as indicated in Fig. 22, has eighty designation columns, each with twelve index points or perforation-receiving positions known as the 9, 8 . . . 1, 0, 11, and 12 positions, and perforations in which are known as the 9, 8 . . . 1, 0, 11, and 12 perforations.

The columns of a card T are perforated according to the information to be listed or transcribed under control of the card, and the various codes designating the information are shown in Fig. 22. The codes may be considered as divided into several zones. The single point zone includes single perforations in any of the 9, 8 . . . 1, 0, 11, and 12 positions of a card column. The 9, 8 . . . 1, 0 perforations in this zone represent, respectively, these several digits, the 11 perforation represents a tabular operation, and the 12 perforation represents a carriage return operation. The 12 zone comprises a common 12 perforation plus one of the perforations 1 to 9, representing letters A to I. The 11 zone comprises the common 11 perforation plus one of the 1 to 9 perforations, representing letters J to R. The 0 zone comprises the common 0 perforation accompanied by a 2 to 9 perforation, representing letters S to Z. The 11—12 zone comprises common 11—12 perforations plus a 1 to 7 perforation, representing different symbols. The 11—12 code alone represents a high speed (H. S.) eject operation to be controlled by the card. In each combination hole code, the common zone perforation or perforations may be referred to as the zone distinguishing perforation, point, or characteristic. In the single point zone, the imperforate portion of the column may be considered as the zone characteristic. The character or function distinguishing points of each zone are the 1 to 9 perforations which may be referred to as the intrazone points or characteristics.

DRIVE MECHANISM

Referring to Figs. 1 and 5, the drive mechanism includes a motor 35. Motor 35 through a coupling 36 rotates a pinion 37 which drives a gear 38 on a shaft 39 carrying a worm 40. Worm 40 meshes with a worm wheel 42 on a sleeve shaft 43 rotatably mounted on a shaft 44.

Main clutch.—One end of the sleeve shaft 43 is provided with a driving clutch ratchet 45 (also see Fig. 18) having four teeth, ninety degrees apart. Fixed to shaft 44, adjacent driving ratchet 45, is a plate 46 formed with four equally spaced notches 46a ninety degrees apart. Loosely carried by shaft 44, adjacent plate 46, is a cam disk 47 with four cam teeth 47a, each adjacent one notch 46a. Plate 46 pivotally carries a clutch pawl 48 having an intermediate tooth 48a to engage a tooth of driving ratchet 45. The free end of pawl 48 carries a stud 48b passing through a hole 46b in plate 46. Adjacent stud 48b, pawl 48 has a pin 48c connected by a spring 49 to a pin 46c on plate 46. The spring tends to move pawl 48 inwardly to engage its tooth 48a with a tooth of driving ratchet 45, but this action is prevented while the high cam portion of a tooth 47a of disk 47 is engaging stud 48b of the pawl. The disk 47 is held in such a declutching position by engagement of the flat side of one of its teeth 47a with the nose of a latch arm 50 fixed

to one end of a shaft 51 which at the opposite end carries the armature lever 52 of main clutch magnet 53. The lower, free end of armature lever 52 is located between a pair of adjustable stop screws 54 which limit the retracted and attracted positions of the armature lever, its shaft 51 and latch arm 50. A spring 55 connected to armature lever 52 and a spring 56 connected to latch arm 50 combine to hold the armature lever in retracted position, with the latch arm in position to engage a tooth of disk 47. Spring 56 connects arm 50 to an impositive latch arm 57 provided with a roller 57a riding on the periphery of disk 46, and adapted to enter a notch 46a of plate 46 to detain, impositively, this plate in one of the four positions, ninety degrees apart, at which the declutching takes effect. Arm 57 is fast to shaft 58 which carries a dependent arm 59 (Fig. 19) located between the adjacent spring blades 60 and 61 of a pair of switches 62 and 63 tending to open. When arm 57a is seated in a notch 46a, switch 62 is closed and switch 63 open. These switches may be referred to as the clutch arm contacts. During rotation of disk 46, arm 57 will be cammed out of notch 46a, causing arm 59 to close switch 63 and permit switch 62 to open. The arm 57 will move into a notch 46a every ninety degrees of rotation of plate 46, intermittently closing switch 62 and opening switch 63.

When main clutch magnet 53 is energized, it rocks armature lever 52, shaft 51, and latch arm 50 counterclockwise (Fig. 18). The latch arm withdraws from an arm 47a, releasing cam disk 47 and enabling spring 49 to move stud 48b inwardly. The stud acts against the curved cam side of a tooth 47a of disk 47 to rock the disk clockwise, bringing the tooth 47a, previously engaged by arm 50 below the nose of the latter. As pawl 48 was rocked inwardly by spring 49, its clutching tooth 48a engaged with a tooth of driving ratchet 45, thereby coupling the driven shaft 44 to the sleeve shaft 43 of the ratchet. With pawl 48 in its inner, clutching position, stud 48b thereof is seated in the crotch between two teeth of cam disk 47, forcing the latter disk to rotate with the pawl. Upon deenergization of main clutch magnet 53, latch 50 intercepts one of the four teeth of disk 47, rocking the latter to cam the pawl 48 out of clutching engagement with ratchet 45. Referring to Figs. 5 and 12, driven shaft 44 rigidly carries a pinion 65, meshed with three sun gears 66 rotatably carried by the three arms of a carrier 67 which is fixed at its center to the reduced end of the hub sleeve 68a of a normally stationary disk 68. With disk 68 stationary, carrier 67 is at rest, and sun gears 66 are capable only of a simple rotation by pinion 65. Rigid with each gear 66 is a pinion 69 meshed with a gear 70 fast to one end of a sleeve 71 surrounding shaft 44. To the opposite end of the sleeve 71 is fast a pair of gears 72 and 73. With shaft 44 coupled, as previously explained, to driving ratchet 45 for rotation, and with driven clutch disk 68 held against movement, pinion 65 of shaft 44 actuates gearing 66, 69, 70, 72, and 73 as a simple train of gearing. Gears 72 and 73 then rotate at normal speed.

Gears 72 and 73 on shaft 71 drive elements of the control section including card feed means which will be described later. During normal speed operation of these gears, the card is fed at a speed such that one column thereof traverses a given reference line during one-quarter turn of

main clutch shaft 44. The period of such travel of a card column is equal to but not coincident with one cycle point of the card cycle indicated in Fig. 20. The card cycle may be considered as the interval between arrival at a reference line of similar points of successive cards. During eighty points of the card cycle, the eighty card columns of a card traverse analyzing means described subsequently. A gap of ten cycle points then occurs before the next card cycle begins on the next card.

Zoning cycle commutators.—Shaft 39 (Fig. 5) is driven continuously by the motor and carries commutators HS (also see Fig. 21) which may be referred to as the zoning cycle commutators. The speed of shaft 39 is four times that of main clutch shaft 44, so that one revolution of this shaft, as well as of its commutators HS corresponds to a quarter turn of shaft 44, which in turn corresponds, during normal card feed, to one card cycle point, as explained before. The revolution of shaft 39 may be referred to as the zoning cycle (Fig. 21) which during normal card feed, is equivalent to one card cycle point.

Shaft 39 also carries a zoning cycle index wheel 110 to index the zoning cycle positions of shaft 39 and the element actuated thereby.

To the left end (Fig. 1) of shaft 39 is fixed a bevel gear 112 which meshes with a bevel gear 113 on a downwardly inclined shaft 115.

Drive for zoning unit.—Shaft 115 at its lower end has a bevel gear 117 meshed with a bevel gear 118 on a horizontal shaft 119 (see Figs. 1, 2, and 7). Shaft 119 is provided with a pin 120 seated in the bayonet slot 121 of a sleeve coupling 122 mounted on the shaft. In line with shaft 119 is a shaft 123 which has a transverse, coupling pin 123a (Fig. 7) slidable into the open, end slots 122a of coupling 122. A spring 124 urges coupling 122 towards the left (Figs. 2 and 7) for maintaining the rear end of the horizontal portion of the bayonet slot 121 in engagement with pin 120. In this position, as indicated in Fig. 7, the slots 122a of the coupling sleeve 122 are receiving the pin 123a, thereby coupling shafts 119 and 123 for common rotation. To uncouple shaft 123 from shaft 119, coupling sleeve 122 is forced rearwardly until pin 121 is at the vertical portion of the bayonet slot, withdrawing slots 122a from pin 123a, and then the coupling sleeve is rotated to engage the pin 120 in the vertical portion of the bayonet slot, thereby maintaining the coupling sleeve in rear, release position.

The main parts of the actuating mechanism have now been explained. The units of the machine driven thereby, the control section and the code translating or zoning unit will be explained in order.

60   *The control section (card handling section)*

Referring to Figs. 1, 2, and 5, gears 72 and 73 of the clutch-driven shaft 71 operate the card reading or handling unit or control section. Gear 73 meshes with and drives a gear 128 fixed to a cross shaft 129 on which are mounted commutators CF, which may be referred to as the card feed commutators. Shaft 129 and the parts mounted thereon and including commutators CF make one revolution for each card cycle. As shown in Fig. 5, a disk 130 is attached to gear 128. This disk 130 is suitably graduated to indicate the card cycle, and may be referred to as the card cycle indicator.

Card picker means.—Referring to Fig. 2, shaft

129 carries complementary cams 131 for engaging rollers 132 and 132' provided on opposite arms of a lever 133. Lever 133 is connected by a link 134 to a picker slide 135 provided at the rear with a picker knife 135' for engaging the rear edge of the bottom card T of the stack of cards in supply magazine 136. The cards are stacked in magazine 136 in the predetermined order in which their data are to be listed, and the cards lie lengthwise in the magazine, with the columns extending crosswise. During each card cycle or revolution of shaft 129, its cams 131, acting through lever 133, link 134, and slide 135, reciprocate the picker knife 135' to feed the bottom card out of the magazine 136 and into the grip of upper and lower feed rollers 137 and 138. Since shaft 129 makes one revolution each card cycle, one card is fed to feed rollers 137 and 138 each card cycle.

Card cycle program means.—One end of card cycle shaft 129 fixedly carries a driver 143 (see Figs. 1, 16, and 17) having a pair of spaced studs 143a and 143b to fit into holes in the side of a card cycle program drum 144. The studs are of different sizes and their receiving holes are of corresponding sizes, so as to permit the drum to be placed on the driver in predetermined relation thereto. The hub of driver 143 is hollow to rotatably and slidably receive the shank of a hand knob 145, urged inwardly towards the side of drum 144 by a coil spring 146 inside the hub of the driver. Hand knob 145 is provided with a clamping block 145' rectangular in shape, adapted to move through a similarly shaped hole 144' in the program drum. By turning the knob 145 to align block 145' with hole 144', the drum 144 is left free to be removed from driver 143. By turning the knob to bring its plate 145' at right angles to hole 144' (as indicated in Fig. 17) the block 145', under the influence of spring 146, firmly clamps the drum to driver 143.

In above manner, card cycle program drum 144 is rigidly but removably coupled to shaft 129 for one revolution each card cycle.

Drum 144 is constructed similarly to a spool with side flanges 144a. Each flange is similarly provided with ninety, equally spaced, radial slots 144b. There are ninety points in a card cycle (see Fig. 20), so that each of the ninety slots 144b corresponds to a definite point of the card cycle. The slots are numbered to indicate the points of the cycle to which they correspond. Each of flanges 144a is formed below the notches 144b with an inwardly extending annular bead 144c. Each of the notches 144b is designed to insertibly receive a spring clip 147. Each clip is generally U-shaped with the legs 147a bent in the form of angles, with the intermediate portions 147b projecting outwardly beyond the legs, and with the cross piece or head 147c connecting the spaced intermediate portions and legs. To place a clip on the drum flanges 144a, the legs of the clip are pinched together to enable them to be inserted between the flanges with the apexes of the leg angles located below beads 144c. As the clip is inserted, the intermediate portion 147b moves into the selected aligned slots 144b of the two flanges, with the head 147c extending across the flanges and between the aligned slots. The legs of the clip, after insertion, tend to spread, thereby gripping the insides of the flanges, while the beads 144c engage the leg angles to prevent radially outward movement of the clip. Since the intermediate portion 147b of the clip is seated in the aligned slots 144b, the

clip is held against circumferential movement. Thus, clips 147 may be inserted on the drum 144 at desired points corresponding to points of the card cycle.

5 Adjacent drum 144 is a subframe 148 mounting a shaft 154 rotatably carrying a pinion 168. The forward, hook end of a spring blade 170 is seated between the teeth of pinion 168 and is below a companion blade 171, the blades carrying 10 contacts 172 between them. When a head of clip 147 rides past pinion 168, it imparts an eighth turn thereto, rotating it a single tooth distance. As pinion 168 rotates, a tooth thereof transiently lifts blade 170, closing contacts 172 15 momentarily. Contacts 172 are the zero elimination contacts, which, in a manner to be explained later in connection with the circuit, eliminate the reading out and printing of zero designations from columns of a numerical card field preceding the column bearing the first significant digit 1 to 9.

Card feed rolls and analyzer.—Gear 72 of the clutch-driven shaft 71 meshes with a gear 175 on the shaft of lower card feed roller 138 (see Figs. 1, 2, and 4). The shaft of the lower roller has a gear 176 meshed with a gear 177 on the shaft of upper feed roller 137, so that the upper and lower feed rollers rotate in unison. As previously described, picker blade 135' feeds a card T out of supply magazine 136 and into the grip of feed rollers 137 and 138 each card cycle. The feed rollers continue the feed of the card moving it at the rate of one column each cycle point.

Between the mouth of the supply magazine and feed rollers 137 and 138 is arranged a card lever 178 (Fig. 2) which is engaged and cammed down by the card traveling to the feed rollers, for closing card lever contacts 179 during travel of the card.

Upper feed roller 137 is a conductive roller acting as the common of the card analyzing means. Coacting with roller 137 are thirteen sensing brushes SB—9 to 0, 11, 12, and c, to respectively sense index positions 9 to 0, 11 and 12 of a card column, while brush SB—c acts as a common return brush, being located to the side of the card and in constant engagement with roller 137 (see Fig. 4). Lower feed roller 138 is grooved so as to hold the free ends of the brushes in predetermined transverse spacing, and enable the brushes to extend substantially in tangential engagement with the lowest part of the feed and contact roller 137 in order to sense the card.

The above described card sensing means, 55 SB—137, analyzes the perforations of the card columns in succession, one column after another, to control the decoding, interpreting, or zoning system to be described later.

Card stacker.—As a card is fed by the rollers 60 137 and 138 past the analyzing means, it moves underneath a flexible plate 180, supported at the rear end, underneath a weighted plate 181 pivoted at its rear end, and into delivery magazine 182. Both plates 180 and 181 are cut out to permit a soft rubber arm 183 to rotate through and past the plates, so as to wipe the card and complete its ejection into the delivery magazine. Arm 183 is carried by a shaft 184 on which is a gear 185, driven through gears 186, 187, and 188 from gear 175 on the lower feed roll shaft. The gear ratio 65 is such that arm 183 makes one revolution each card cycle to complete the ejection of the card analyzed during this cycle.

The stack of ejected cards in delivery magazine 70 182 rests on a bottom plate 190 hinged at its

front end on a pivot 191. To the bottom of plate 190 is fast a bracket 192, passing through a slot 193 in the side wall of the magazine and rigidly provided outside the latter wall with a rack sector 194. Sector 194 meshes with a gear 195 (see Figs. 2 and 3) coaxing with a horizontal rack 196 provided on a sleeve 197 which slides inside a fixed tube 198. The rack 196 passes through a narrow slot in tube 198, preventing rotation of the sleeve 197. Between tube 198 and sleeve 197 is a coil spring 199 tending to move the sleeve to the left (Fig. 3). With no cards on plate 190, spring 199 is holding sleeve 197 at its left hand limit. As the cards stack up on plate 190, their weight depresses rack sector 194 which, through gear 195 and rack 196, causes sleeve 197 to move to the right, against resistance of spring 199. When the delivery magazine is full, the weight of the stack has moved bottom plate 190 downwardly to an extent sufficient to engage the lower edge of bracket 192 with an insulating tab 200 fixed to the lower blade 201 of a switch 203, thereby opening such switch to interrupt operation of the card feed unit, in a manner which will be explained later.

Zoning unit

The zoning unit includes twelve horizontal, parallel combination or comb bars 210, disposed one above another, and located at a distance below the typewriter keyboard, as indicated in Figs. 6, 10, and 13. Each comb bar corresponds to an index position of a card column and may be distinguished by referring to it as the comb bar of the correspondingly termed index position. Thus, bars 210-9, 8 . . . 1, 0, 11, 12 correspond to index positions 9, 8 . . . 1, 0, 11, 12, and their positions are indicated in Fig. 13.

Each of the comb bars 210 is formed with front lugs 210a arranged for combination with lugs of the other combs in governing interpretation of a perforated designation code. Each comb also has a single rear lug 210b, and the lugs 210b of the several combs are staggered horizontally to enable each lug to be engaged by the free end of one of the twelve staggered armature levers 211, as indicated in Figs. 6 and 8. Each armature lever 211 is operated by one of the twelve zone magnets 212, arranged in two horizontal layers and staggered to enable the armature levers to dispose their free ends in engagement with the staggered lugs 210b of the several combs 210. A pair of opposite, end guide combs 213 and a central guide comb 214 (Fig. 7) guide the combs 210 for horizontally slidable movement. A spring 215 connected to each comb 210, urges the latter towards the left to a normal position, determined by engagement of a screw 216 (Figs. 6 and 8) carried by the armature 211 with the frame plate 217.

Upon energization of a zone magnet 212, it rocks its armature lever 211 counterclockwise (Fig. 8), causing the armature lever, by engagement with the associated lug 210b, to shift the corresponding comb bar 210 to the right.

Extending in front of the combs 210 are a plurality of spaced vertical levers 218 urged towards the combs by springs 219. The lower tip of each lever follows a cam 220 extending across all the levers and fixed to shaft 123. As previously explained under the heading "Drive mechanism," shaft 123 is continuously rotated, through a coupling 122, from motor-driven continuously rotating shaft 119. Shaft 123 makes one revolution each zoning cycle (Fig. 21), and during normal card feed, one zoning cycle corresponds to a card

cycle point. Once each zoning cycle, cam 220 releases levers 218 for forward movement by springs 219. During each zoning cycle occurring between "1" and "80" of the card cycle (see Fig. 20) during normal card feed, a column code analyzing period is provided during which analyzing means SB-137 is effective to analyze one card column for a designation or code. In accordance with the analysis, selected combs 210 are shifted to the right, to displace their front comb lugs 210a from in front of the lever 218 corresponding to the character or function represented by the analyzed perforated code in the active card column. There will be no other lugs 210a in front of the latter lever 218 but one or more lugs remain in front of the rest of the levers 218. Accordingly, when cam 220 releases levers 218 for inward movement, only one of these levers is enabled to move inwardly to a sufficient extent to bring the shoulder 218a of the lever above a common lift bail 221. Bail 221 extends across all the levers 218 and is provided with rollers 222 at each side following cams 223 fixed to zoning cycle shaft 123. Thus, for each cycle point or analysis of one card column, bail 221 is given one reciprocation. During the rise of the bail, by engagement with the shoulder 218a of that vertical lever 218 which has been released by the combs 210, the bail lifts the lever.

The upper end of each lever 218 is pivotally connected to a lever 224 urged counterclockwise (Figs. 6 and 13) by a spring 225 and pivoted to a link 226. Each link 226 is provided at its upper end with a stud 226a freely passing through a vertically elongated slot 227 in an associated one of the horizontal, operating levers 10 of the transcribing unit. To yieldably and releasably maintain the side of link 226 firmly against the side of the associated lever 10 and prevent accidental withdrawal of stud 226a, a flat spring 228 is fixed to the side of each link 227, the spring and link engaging the associated lever 10 between them. When the lever 218, which has been selected by combs 210, is lifted by bail 221, it rocks lever 224 clockwise (Fig. 6) against resistance of spring 225, thereby lowering link 226 to depress the corresponding operating lever 10. Depression of the lever 10 effects the recording or other function of the transcribing unit, as denoted by the code in the analyzed card column.

As indicated in Fig. 9, the combs 210 have front lugs 210sp. The lugs 210sp of the twelve combs are in vertical alignment and located directly to the left (Figs. 7 and 8) of the vertical lever 218sp. No matter which code combination is sensed on a card T, at least one of the combs 210 will be moved to the right, thereby placing its lug 210sp in front of lever 218sp to prevent its coaction with the lift bail 221. Lever 218sp is operatively connected with the intra-line space operating lever 10-SP. Thus, when any code is sensed and interpreted, causing actuation of one or more of the combs 210, lever 218sp will be blocked against operation, permitting the intra-line spacing of the carriage 24 (see Fig. 6) to occur only as the usual incident to the operation of the lever 10 corresponding to the character whose designation has been found in the analyzed card column.

When the card column traversing the analyzing means is blank, then an operation of intra-line space lever 10-SP is indicated. Thus, failure to sense any perforation in a card column leaves all the combs 210 in their normal positions, with all the lugs 210sp out of the path of lever 218sp which thereby is enabled to move

forward to cooperate with lift bail 221 for operating space lever 10-SP to effect an intra-line spacing of the carriage 24.

During certain operations, including carriage return or line space operation, for the period of each cycle between the departure of one card from the analyzing means and the arrival of the next card, and, whenever main clutch shaft 44 is at rest, none of the combs 210 is actuated. Accordingly, operation of intra-line space lever 10-SP would be effected, undesirably, under control of operating lever 218sp each cycle of shaft 123, unless provision were made to the contrary. To lock out the operating lever 218sp under the above conditions, a space lock magnet 230 (Figs. 8 and 13) is provided, energization of which rocks its armature 231 downwardly to rock a lever 232 clockwise (Fig. 13) against resistance of a spring similar to spring 225. Pivotally suspended from lever 232 is a lock arm 233 urged towards the right (Fig. 13) by a spring similar to spring 219. The lower end of arm 233 is formed with a bent lug 233a, from an intermediate portion of which a tab 233b projects parallel to the side of arm 233. The inward movement of arm 233 is limited by engagement of tab 233b thereof (see also Fig. 8) with the front of the bottom guide comb 234 of the operating levers 218. Thus, upon clockwise rocking of lever 232, effected by armature 231 upon energization of magnet 230, lock arm 233 will be moved vertically upward. The outer, reduced end of lug 233a of arm 233 overlaps operating lever 218sp and normally lies against the back of the lever, entirely below and out of a notch 218'sp formed on the space operating lever (see Fig. 13). When lock arm 233 is lifted as a result of energization of magnet 230, lug 233 moves upwardly into notch 218'sp, thereby locking lever 218sp against inward movement. Thus, even though none of combs 210 is actuated, if magnet 230 is energized, it will cause locking of the space bar operating lever 218sp.

To time the impulses to space lock magnet 230 for each column or cycle point, a switch 235 is provided which is closed by lift bail 221 when the bail is in lower position and which opens when bail 221 rises. Since bail 221 is given one reciprocation each cycle point, switch 235 will open and close once for each cycle point. It is to be understood, however, that switch 235 does not, of itself, close the circuit of magnet 230. The latter circuit will be traced hereinafter.

A "12" perforation occurring alone in a card column indicates a carriage return operation, and analysis of this perforation energizes the magnet 212 of comb 210-12. When comb 210-12 alone is operated, the carriage return lever 218CR (Figs. 7, 8, and 10) is released for coaction with lift bail 221. As lever 218CR is lifted by bail 221, it rocks the connected lever 224 counterclockwise (Fig. 10). Due to the operation of lever 218CR, the carriage return operating lever 10-CR (Figs. 1 and 7) is depressed to effect a carriage return operation of the carriage 24 (Figs. 1 and 6), and as an incident to the carriage return, a line spacing operation occurs, as usual.

Towards the latter part of the revolution of shaft 123 of the zoning system, a cam 250 thereof (Figs. 7, 8, and 10) effects clockwise rocking (Fig. 10) of a lever 251. The upper end of lever 251 bears against the arm 252a of a knock-off bail 252 (also see Fig. 11), which has an arm 252b extending vertically across the right hand

edges of all the combination combs 210. Upon clockwise rocking of lever 251 by cam 250, the upper end of the lever rocks bail 252 clockwise (Fig. 11), causing arm 252b thereof positively to engage and return all the combs 210 to the left. Thus, the combs 210 and the armatures 211 are positively restored at a definite, latter portion of the cycle of shaft 223, after which the springs 215 connected to the combs yieldingly maintain the combs in their restored positions.

The mechanical features of the zoning system have been explained above. Further explanation of its operation will be given as an incident to the description of the circuits hereinafter.

CIRCUITS, TIMING, AND OPERATION

Referring to Fig. 23, with main line switch SW closed, motor 35 is set in operation, the circuit therefor going through safety contacts 141.

In the following description, it is assumed the parts are initially in 0 cycle position of the card cycle (see Fig. 20).

Having brought the first line of a bill form to printing position on platen 20 of the recording unit, and having placed the stack of cards T bearing the data for the bills in supply magazine 136, the operator may now start operations by depressing the start key to close start key contacts ST, forming the following circuit (middle of Fig. 23):

Start key circuit.—From the left side, through contacts ST, normally closed relay contacts R-17b, relay coil R-7, to the right side.

Due to energization of coil R-7 by the Start key circuit, relay contacts R-7b are closed to form the following main clutch circuit (bottom of Fig. 23):

Main clutch magnet circuit.—From the left side, through normally closed recorder unit contacts 28 (also see Fig. 14), normally closed relay contacts R-3b, now-closed relay contacts R-7b, normally closed relay contacts R-22b, R-14c, jumper wire 623, normally closed relay contacts R-10b, main clutch magnet 53 (also see Fig. 5), and to the right side.

With main clutch magnet 53 energized, shaft 71 is now acting through gears 72 and 73 to actuate the card feeding means. At the "0" cycle point, picker 135' (see Fig. 2) is in advanced position, ready to begin its return stroke (see Fig. 20). As the machine is now set in operation for the first card cycle, the picker is moved through its return stroke, and at the end of this stroke, at about the 64th cycle point, the picker is at the rear of the bottom card T in magazine 136 (see Fig. 2). The picker then dwells until about "70" of the card cycle at which point it begins its forward stroke to feed the bottom card to the feed rollers 137 and 138.

The perforation field or width of the first card column or column "1" of the card reaches the line of sensing brushes SB shortly before the "1" cycle point of the card cycle, between the 80th and 90th divisions of the "0" cycle point, as indicated by the upper, "Card brush" timing line, in the zoning cycle chart, Fig. 21. The "Card brush" line indicates the periods of sensing of perforations in successive card columns by brushes SB. Between "0" and "55" of one zoning cycle, the major, latter portion of a hole in one column is sensed and during this period, commutator HS-1 is made, so as to render the sensing effective to perform an analysis, as will be further explained hereinafter. After this effective analyzing period of one card column during one zoning cycle, the

brushes SB sense, between "85" and the end of the zoning cycle, the beginning of the perforation of the next column, but with HS-1 broken, this sensing is not effective to perform an analysis.

During the first card cycle (Fig. 20), the picker started moving the first card out of magazine 136 and to feed rolls 137 and 138. During its travel to the feed rolls, the card engages card lever 178 and cams it down to close card lever contacts 179 (Fig. 2) after the beginning of the 82nd cycle point. Closure of contacts 179 establishes the following circuit (top of Fig. 23):

Card lever circuit.—From the left side, through contacts 179, relay coils R-1 and R-2, to the right side.

The operator need only hold the start key depressed until the first card enters the feed rolls 137 and 138, since by then card lever contacts 179 have closed, and the Card lever circuit has been established to energize coils R-1 and R-2. Coil R-2 now has closed contacts R-2b to shunt start key contacts ST through the following circuit:

Start key shunt circuit.—From the left side, through relay contacts R-2b, stop key contacts SK, stacker contacts 203 (also see Fig. 2), stick contacts R-1a of previously energized relay coil R-1, the relay coil, and to the right side.

Relay coil R-1 now remains energized until either the cards are exhausted from supply magazine 136, causing the card lever contacts 179 to open and eventually deenergize coil R-2 with consequent opening of contacts R-2b, or upon depression, at will, of the stop key to open contacts SK, or when the stacker magazine 182 is full, causing contacts 203 to open.

There is a gap between successive cards feeding from magazine 136, and the lagging edge of the leading card will leave card lever 178 and permit card lever contacts 179 to open at "78" of the card cycle, while the forward edge of the following card will not cause contacts 179 to make again till after "82" of the same card cycle. To maintain coils R-1 and R-2 energized during this open interval of card lever contacts 179, commutator CF-4 makes (see Fig. 20), shunting contacts 179 through the following path (the top of Fig. 23):

Card lever shunt.—From the left side, through commutator CF-4, stick contacts R-1a, coils R-1, R-2, to the right side.

If the stack of cards is exhausted, contacts 179 will not have been reclosed and when commutator CF-4 breaks at "84" of the card cycle, coils R-1 and R-2 will be deenergized. Contacts R-2b will open and the Start key shunt circuit will break to deenergize coil R-1. As a result, contacts R-1b will open to break the Main clutch magnet circuit. Main clutch magnet 53 remains energized, however, till the end of the card cycle through a shunt circuit formed through commutator CF-5 (see Fig. 20), which makes at "82" and opens at "89". The making of commutator CF-5 shunts contacts 28, R-3b, R-7b, R-22b, R-14c, and R-10b of the Main clutch magnet circuit, permitting clutch magnet 53 to remain in effect until the beginning of the 89th cycle point. The main clutch is uncoupled, as a result, at the 80th division (see Fig. 21) of the 89th cycle point.

The analyzing or card reading period of a card cycle is indicated by the top line of Fig. 20 and extends from "1" through "80," during which period, the Card read commutator CF-1 is made. The Card lever circuit has energized coil R-1

to close contacts R-1b, forming the following circuit during the card reading period:

Coil R-9 circuit.—From the left side, through commutator CF-1, contacts R-1b, wire 310, coil R-9, to the right side.

Coil R-9 now closes the left side of transfer contacts R-9b (near the top, right of Fig. 23) and opens the right side of these transfer contacts. This condition of the contacts R-9b endures through the card reading period under control of commutator CF-1 and is repeated every card cycle as long as cards continue to feed and, through the card lever circuit, maintain relay coil R-1 energized to hold contacts R-1b closed in the coil R-9 circuit.

As an example of an analyzing circuit, assume a "12" perforation is being analyzed, forming the following circuit:

"12" analysis.—From the left side, through commutator CF-1, contacts R-1b, zoning commutator HS-1 (see Fig. 21), normally closed contacts R-13b, clutch arm contacts 63 (see Fig. 19 for construction and Fig. 21 for timing), common brush SB-c, contact roll 131, brush SB-12, the left and now-closed side of transfer contacts R-9b, through the "12" comb magnet 212, and through relay coils R-3 and R-4, to the right side.

As indicated by above analyzing circuit and by reference to the card cycle chart, Fig. 20, commutator CF-1 times the card reading period, so that after the 80th or last card column has passed brushes SB, the engagement of the brushes with the bare contact roll 131 will be ineffective to form any analyzing circuits.

When the main clutch is at rest, clutch arm contacts 63 are open to prevent formation of any of the analyzing circuits.

Comb magnet 212-12, upon energization, shifts its associated comb bar 210-12 to the right (Fig. 8).

When the analyzing means senses one of the perforations 8 to 1, the analyzing circuit is as follows:

Digit or intrazone analysis.—From the left side, through CF-1, R-1b, HS-1, R-13b, 63, brush SB-c, common roller 131, the active one of the brushes SB-1 to 9 sensing the interzone perforation 1, 2 . . . 8, or 9, the comb magnet 212 in series with the active brush, and through common relay coils R-5 and R-16 to the right side.

If a column contains a zone perforation plus one of the intrazone perforations 1 to 9, designating an alphabetic character, a pair of comb magnets 212 is simultaneously energized, moving two combs 210 to the right (Figs. 7 and 8), in readiness to release the lever 218 corresponding to the alphabetic character denoted by the sensed zone and intrazone holes in the card column. If only one perforation 0 to 9 occurs in a column, indicating a digit, only one comb magnet 212 is energized and the associated comb 212 moved to the right ready to release the lever 218 corresponding to the analyzed digit perforation.

The forward movement of the selected lever 218 does not occur until cam 220 (Figs. 6, 10, and 13) permits the levers to drop off the high point of the cam. This occurs shortly before "20" of the zoning cycle (Fig. 21). Before analysis of the column designation and resulting displacement of selected combs 210, the lever 218 corresponding to this designation is in front only of lugs 210a (Fig. 9) of these combs. The displacement of these combs removes their lugs from in front of the lever 218 corresponding to the ana-

75

lyzed designation, thus selecting this lever for operation. There is at least one lug 210a in front of every other lever 218. When cam 220 releases levers 218, they move forward to sense comb lugs 210a (see Fig. 9). All the levers 218 will be stopped by the comb lugs with the exception of the selected lever which corresponds to the analyzed character. This selected lever moves forwardly between lugs 210a of the combs, thereby locating its shoulder 218a above lift bail 221 (Figs. 10 and 13). At about "24" of the zoning cycle, circuit breaker HS-1, which times the duration of the analysis of a column perforation, opens and breaks the analyzing circuits to deenergize the comb magnets 212. Springs 215 (Figs. 7 and 8) now tend to return the previously actuated combs 210 but this is prevented at this time by engagement of sides of lugs 210 thereof with the selected lever 218 which has moved forwardly between these lugs.

At "50" of the zoning cycle, lift bail 221 rises and by engagement with shoulder 218a of the forwardly positioned, selected lever 218, lifts the latter to operate the associated lever 10 for causing a type bar 18 (see Fig. 6) to strike platen 20 at about "81" of the zoning cycle to record the character corresponding to the analyzed designation. At "90" of the zoning cycle, cam 220 has withdrawn the selected lever 218 from all the lugs 210a of combs 210, thus releasing the previously actuated combs for restoration by their springs 215. Shortly thereafter, at about "95" of the zoning cycle, cam 250 (Figs. 7 and 10) operates lever 251 to cause bail 252 to positively restore and align combs 210 in normal positions.

The above explanation indicates the operations and timing thereof occurring during a zoning cycle or cycle of the zoning or transcribing system and which corresponds, when the card is being fed at normal speed, to a card cycle point.

These operations cause the transcribing means under control of a designation in a card column to transcribe and record the corresponding character.

As previously explained, the failure of any of the combs 210 to be actuated allows the lever 218sp to move forward for controlling an intra-line space operation. Any comb 210 when actuated interposes a lug 210sp (Fig. 9) in the path of the lever 218sp, preventing effective operation thereof. The absence of any perforation in a card column allows all the combs 210 to remain in normal position and permit the intra-line space lever 218sp (Figs. 7, 8 and 13), upon release by cam 220 at about "20" of the column cycle (Fig. 21), to move forwardly above lift bail 221. As a result, during the zoning cycle, lever 218sp is effective to operate lever 10-SP (Figs. 1 and 13) for effecting intra-line spacing.

Intra-line space lock.—As already explained, when none of the combs 210 is actuated, lever 218sp (Fig. 13) is normally free to move forward and operate lever 10sp to cause intra-line spacing of the recording unit carriage 24 (Fig. 6).

A gap of ten cycle points occurs between successive cards, during which none of the combs 210 is actuated, the analyzing circuit line being broken by commutator CF-1 (see Fig. 20). During each of the zoning cycles or revolutions of shaft 123 occurring within said gap, when cam 220 releases lever 218sp, forward movement of the lever, while not blocked now by combs 210, will be prevented by energization of magnet 230.

It is also desired to lock the lever 218sp against operation if the main clutch is uncoupled dur-

ing any zoning cycle, particularly during a zoning cycle corresponding to a cycle point occurring during the card reading period, "1" to "30" of a card cycle.

5 The manner in which the magnet 230 is energized, under above conditions, to lock the space lever 218sp will now be explained. The circuit for magnet 230 is as follows (middle of Fig. 23):

Space lock magnet circuit.—From the left side, through line 311, through either contacts R-9a or the clutch arm contacts 62, through lift bail contacts 235 (also see Fig. 13), and space lock magnet 230, to the right side.

Contacts R-9a are opened by coil R-9 energized during the card reading period of a cycle by the previously traced coil R-9 circuit. Between card reading periods, coil R-9 is de-energized, permitting contacts R-9a to close. Thus, the Space lock magnet circuit will be automatically established during the ten cycle point gap between successive cards or while the brushes SB are wiping the bare contact roll 137. During this gap, shaft 123 makes ten revolutions and none of the combs 210 is actuated, but lever 218sp

25 remains locked by magnet 230 against operation by the lift bail 221. In above manner, under control of contacts R-9a, intra-line spacing of the recording unit is prevented between card reading periods.

30 If the main clutch is stopped, clutch arm contacts 62 make (see Fig. 19) and remain closed while the main clutch is at rest and while shaft 123 continues to rotate and perform zoning cycles. As the main clutch is at rest, the card feed has

35 been interrupted and during this period, the circuit for magnet 230 forms through closed contacts 62. As indicated in the zoning cycle chart (Fig. 21), the main clutch disengages at "80" of the zoning cycle or after the operations under

40 control of the last-analyzed card column have been completed. Lift bail contacts 235 do not close till "90" of this zoning cycle. At this point, with contacts 62 closed, the Space lock magnet circuit forms, energizing magnet 230 to prevent

45 forward movement of lever 218sp above lift bail 221. This circuit remains in effect till "75" of the next zoning cycle, but by then the lift bail 221 has risen and, even if lever 218sp were to move forward, it would be too late for the shoulder 218a thereof to coact with the lift bail. Thus, during the zoning cycle following disengagement of the main clutch, intra-line spacing is prevented.

50 As long as the main clutch remains disengaged, contacts 62 stay closed and the above locking action is repeated each zoning cycle. In above manner, when the main clutch is at rest and card feed has been interrupted, intra-line spacing of the record sheet on platen 20 is prevented under control of clutch arm contacts 62.

Intermediate column carriage return code.—When an intermediate card column (between 1 and 80 or 2 through 79) is punched with a carriage return code "12," the sensing of this code by the analyzing means forms the previously traced "12" analysis circuit, energizing comb magnet 212-12, and relay coils R-4 and R-8.

55 Energization of comb magnet 212-12 causes operation of lever 218CR (Figs. 7, 8, 10) in turn causing lever 10-CR (Fig. 1) to operate the carriage return and incidental line spacing mechanism.

60 Coil R-8 closes contacts R-8b to form the following circuit:

Coil R-3 circuit.—From the left side, through zoning cycle commutator HS-2 (see Fig. 21),

line 316, normally closed relay contacts R-16a and R-20a, contacts R-8b, coil R-3, to right side.

Coil R-3 closes contacts R-3a to form a shunt circuit operative after contacts R-8b open due to breaking of the analyzing circuit at about "24" of the zoning cycle. This shunt circuit is as follows:

Coil R-3 shunt.—From the right side, through coil R-3, contacts R-3a, left hand margin contacts 33 (also see Fig. 15), to the left side.

Coil R-3 opens contacts R-3b in the Main clutch magnet circuit, deenergizing clutch magnet 53 to stop card feed at "80" of the same zoning cycle (see Fig. 21) in which the carriage return code was sensed. As the carriage return operation is effected, contacts 28 (Fig. 14) also open, causing an additional break in the Main clutch magnet circuit. The card feed will now stop until the carriage return mechanism returns to normal to cause contacts 28 to reclose and until the left margin is reached, at which point the left margin stop extension 34a (Fig. 15) opens contacts 33, and the next line of the bill form is in position to receive the transcription from the following card column. As contacts 33 open, the stick circuit of coil R-3 opens, and contacts R-3b reclose. With termination of the carriage return operation, contacts 28 also reclose, and as contacts R-3b have now closed, the Main clutch magnet circuit is reestablished, resuming card feed.

In above manner, spaced intermediate card columns may have carriage return codes to cause the date of a single card T to be transcribed on successive lines of a bill form. It is to be noted, however, that normally, in the absence of an intermediate card column carriage return code, all the data of a single record card will be transcribed on a single line of a bill form.

Normal carriage return.—Following the passage of the last card column of each card past the analyzing means, a cyclic carriage return normally occurs, as follows: After the last card column has been read, commutator CF-1 (Fig. 20) breaks, opening the coil R-9 circuit. As coil R-9 is deenergized, it permits the right side of transfer contacts R-9b to close, which occurs after the analyzing period of column 80. After the right side of contacts R-9b close, commutator CF-3 (Fig. 20) makes. Commutator CF-4 already has made, and when commutator CF-3 makes, the following circuit forms (top of Fig. 23):

Coil R-26 circuit.—From the left side, through commutator CF-4, contacts R-1a, normally closed R-18b contacts, commutator CF-3, coil R-26, to the right side.

Coil R-26 closes contacts R-26a, and with the right side of transfer contacts R-9b already closed, the following circuit is established (upper part of Fig. 23):

Normal C. R. circuit.—From the right side, through coils R-4, R-8, comb magnet 212-12, the right side of contacts R-9b, contacts R-26a, contacts R-1a, commutator CF-4, and to the left side.

As a result of energization of magnet 212-12, a carriage return operation occurs. This normal, cyclic carriage return is effected at the end of the card reading period, normally causing the data of each card to be recorded on a separate line. As an incident to the normal or cyclic carriage return, card feed is interrupted under control of the coil R-3 circuits, formed

in the manner explained in connection with the Intermediate column carriage return operations.

Zero elimination.—In order to explain zero elimination, the "0" analyzing circuit will be traced first. Normally, upon sensing of a "0" code in a card column, the following circuit forms:

"0" analyzing circuit.—From the left side through commutator CF-1, contacts R-1b, commutator HS-1, relay contacts R-13b, contacts 63, common brush SB-c, contact roll 137, brush SB-O, normally closed zero elimination contacts R-25b, comb magnet 212-O, coil R-24, and to the right side.

When a "0" code occurs alone in a card column outside the selected numerical card field or within the numerical field but after the first significant digit representation, the above "0" analyzing circuit is established, causing the printing of the digit "0." It is desired, however, to prevent the formation of the above circuit when the "0" code occurs within the selected numerical card field but before the first significant figure designation of this field. By preventing formation of the "0" analyzing circuit, the printing of the "0" by the transcribing and recording means is prevented. Further, since the "0" analyzing circuit is suppressed, all the combs 210 remain in initial position, and as a result, the lever 218sp is permitted to move forward, causing an intra-line spacing operation to occur. Thus, for each column of a numerical card field bearing a "0" code preceding the column bearing the designation of the first or highest order significant digit, the recording of a "0" will be prevented and instead an intra-line spacing operation will occur. The numbers in the selected, corresponding numerical fields of successive cards are listed by the recording apparatus one

above another, due to the carriage return operation which occurs at the end of each card cycle, as explained above. The numbers are thus recorded in lists, within a predetermined, vertical, numerical field of the receiving sheet P, and this field may be considered as including denominational order columns, each corresponding to a denominational order column of the numerical card field. As explained above, when the "0" analyzing circuit is suppressed, the "0" digit is not printed in the corresponding order column of the sheet P, but instead the sheet is spaced to bring the next order column thereof to printing position. In this manner, the numbers of the successive cards which are printed in list form on the sheet P have their digits located in the proper denominational order columns along the list.

The zero elimination means is to prevent "0" codes of selected numerical card fields from being transcribed when such codes occur above the highest order significant figure of the numerical field. The "0" codes, however, are to be transcribed when they are in columns of the numerical card field following the column bearing the first significant figure. Further, since successive cards have correspondingly located numerical card fields, the zero elimination means may come into play at the same time during each of successive cycles, and this is effected under control of the cyclically operating program drum 144. As previously explained, clips 147 may be set on drum 144 (Figs. 16 and 17) to ride past pinion 168 and turn the latter to cause contacts 172 to close for effecting elimination of zero printing before the first significant digit of a numerical

quantity. Thus, if card columns 50 to 58, inclusive, constitute a numerical card field the preceding column 49 is to be sensed in the normal manner for a zero code, and a clip 147 is set in the drum notch corresponding to column 49. After analysis of the code in card column 49 and as a consequence of which the transcription of the code has been determined and will be brought to completion by the zoning and recording units, the clip set in notch "49" of drum 144 closes contacts 172 at "25" (see Fig. 21) of the 49th cycle point.

Closure of contacts 172 forms the following circuit (middle of Fig. 23):

Zero elimination program circuit.—From the right side, through coil R-25 and contacts 172, to the left side.

Coil R-25 closes contacts R-25a to by-pass program drum contacts 172 which are closed only momentarily, through the following circuit:

Zero elimination holding circuit.—From the right side, through coil R-25, contacts R-25a, normally closed R-16b contacts, and to the left side.

Contacts R-16b remain closed till coil R-16 is energized. It will be recalled that coil R-16 is in the Digit or intrazone analysis circuit and is energized when any of digits 1 to 9 are sensed in a card column. Thus, upon the occurrence of the first significant digit in the numerical card field, the circuit of coil R-25 will open because of the breaking of contacts R-16b.

Coil R-25, during its period of energization, maintains contacts R-25b of the "0" analyzing circuit open. As long as contacts R-25b are open, the "0" analyzing circuit cannot be established, so that any zero codes punched in the columns of the numerical card field will be ignored, and no recording of zeros will take place under control of the zero codes until contacts R-25b reclose. When the first significant digit 1 to 9 is sensed in a column of the numerical field, an intrazone analysis circuit will form, energizing coil R-16 which opens contacts R-16b to break the Zero elimination holding circuit. Coil R-25 thereupon is deenergized, permitting contacts R-25b to reclose, so that any zero code in a column following the first one in which a perforation 1 to 9 is sensed will be effective to cause recording of the "0" designated by the zero code.

If zero elimination is not desired, contacts R-25b may be shorted by a jumper wire 322.

Brushes SB and roll 137 may properly be considered as the designation-sensing means, the sensing means and the circuits therethrough may be referred to as the analyzing or reading means for the record, and the circuits of the reading or analyzing means may be identified, for convenience, as the analyzing or reading circuits.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination, means to sense digit designations representing a plural order number, recording mechanism to record the equivalents of

the designations, means controlled by the sensing means for causing operation of the recording mechanism according to the sensed designations, means to suppress effectiveness of the sensing means to detect zero digit designations, and means controlled by the sensing of the first significant digit designation of said number for restoring the sensing means to effectiveness to detect subsequent zero designations of the number.

5. In combination, means to detect zero digit designations, and means controlled by the sensing of the first significant digit designation of said number for restoring the sensing means to effectiveness to detect subsequent zero designations of the number.

2. In a machine acting on a record having a numerical field bearing a plurality of designations representing a multi-denominational order number; the combination of means to read the designations, means controlled by the reading means to manifest the number represented by the designations, means to prevent the reading of zero digit designations, and means controlled by reading of the designation of the first significant figure for restoring the reading means to effectiveness for reading zero digit designations occurring within the numerical field after the first significant digit designation.

3. In combination, means to sense digit designations of a plural order number in succession, starting with the highest order, mechanism to record the equivalents of the designations, means controlled by the sensing means for causing the recording mechanism to operate according to the sensed designations, means to render the sensing means ineffective to detect zero designations, and means controlled by the sensing of the first significant digit designation of the number for rendering the sensing means effective to detect subsequent zero designations of the number.

4. In combination, means to sense digit designations of a plural order number in succession, starting with the highest order, mechanism to record the equivalents of the designations in successive columns of a sheet and including devices selectively operable according to the designations and mechanism operable as an incident to each operation of the devices for effecting a relative column spacing movement between the sheet and the devices, means controlled by the sensing means for selectively operating the devices according to the sensed designations, means to render the sensing means ineffective to detect zero designations, means operable in synchronism with the successive sensing of the designations for normally effecting operation of said column spacing mechanism in the absence of detection of a designation by the sensing means, and means controlled by the sensing of the first significant digit designation of the number for restoring the sensing means to effectiveness to sense subsequent zero designations.

5. In combination, sensing means to sense digit designations of a plural order number, circuits extending through the sensing means and closed by the sensing of designations, one of said circuits being a zero designation circuit adapted to be closed by the sensing of a zero digit designation, mechanism to record the equivalents of the designations, means controlled by the circuits upon closure thereof for causing operation of the recording mechanism to record the equivalents of the sensed designations, means to suppress closing of the zero designation circuit, and means controlled by the circuit closed by the sensing of the first significant digit designation of the number for rendering the suppressing means ineffective so as to enable the zero designation circuit to be closed by the sensing of subsequent zero designations of the number.

6. In a machine operating in successive cycles on successive records bearing corresponding numerical fields in which numbers are represented by digit designations; the combination of means controlled by the designations of a numerical field of a record during a cycle for manifesting the number represented thereby, means to suppress the manifestation of zero digits under control of zero digit designations, automatic, cyclically operating means acting each cycle to place the suppressing means in operation, and means responsive to operation of the designation-controlled means under control of the first significant digit designation in a numerical field for automatically rendering the suppressing means ineffective to suppress manifestation of zero digit designations following the first significant digit designation in a numerical field.

7. In a machine operating in successive cycles on successive records bearing corresponding numerical fields in which numbers are represented by digit designations; the combination of means controlled by the designations of a numerical field of a record during a cycle to effect recording of the number represented thereby, means to suppress recording of zero digits, settable program means operated recurrently in successive cycles to place the suppressing means in operation at the same point of each cycle, and means responsive to operation of the designation-controlled means under control of the first significant digit designation in a numerical field for automatically rendering the suppressing means ineffective to suppress recording of zero digits following the first significant digit of a number represented in a numerical field.

8. In a machine for acting on successive records on which plural order numbers are represented in corresponding numerical fields of columns, each of which may bear any of different digit designations; designation-reading means, means to move each successive record and the reading means relatively to each other to cause the reading means to read the columns in succession for designations, recording mechanism to record the equivalents of the designations, means controlled by the reading means for causing operation of the recording mechanism to record the designation equivalents, means to suppress recording of zero designation equivalents, means operating in synchronism with the relative movement between each record and the reading means for rendering the suppressing means effective at a predetermined point of the relative movement between each record and the reading means, and means controlled by the reading means upon reading of the first significant digit designation of a numerical field for rendering the suppressing means ineffective to suppress re-

cording of the equivalents of zero designations following the first significant digit designation of a numerical field.

9. In a machine acting on a record bearing digit designations representing a plural order number, designation-reading means, means to effect travel of the reading means and the record relatively to each other to cause different designations to be read out successively, recording mechanism to record the equivalents of the designations, means controlled by the designation-reading means for controlling the recording mechanism according to the designations, a device for suppressing recording of zero designation equivalents, a controller and means controlled thereby for rendering the suppressing device effective, means for moving the controller and the means controlled thereby relatively to each other in synchronism with the relative travel between the record and reading means to cause the suppressing means to be rendered effective at a selected point of said relative travel, said controller and the means controlled thereby being relatively adjustable to vary the selected point of their coaction, and means controlled by the reading means upon reading of the first significant digit designation of a numerical field for rendering the suppressing means ineffective to suppress recording of zero designation equivalents which may follow the first significant digit of the number represented on the record.

10. In a machine acting on a record on which a number is represented in a numerical field of successive columns, each of which may bear any of different digit designations, means to read the designations of the columns in succession, recording mechanism to record equivalents of the designations, means controlled by the reading means to cause operation of the recording mechanism according to the designations, a device to suppress recording of zero designation equivalents, a controller comprising a contrivance traveling in synchronism with the successive reading of the columns and an element settable on the contrivance at a selected one of spaced positions thereof, each such position corresponding to a column of the record, means controlled by the element, at a point of the travel of the contrivance depending on the position in which the element is set, for rendering the suppressing device effective, and means controlled by the reading means upon reading of the first significant digit designation of a numerical field for rendering the suppressing device ineffective to suppress recording of equivalents of zero designation following the first significant digit designation in said field.
